UNITED STATES PATENT OFFICE.

JOSEPH L. SCHRAG, OF ODESSA, WASHINGTON.

MULTIPLE-SECTION GRAIN DRILL.

Application filed January 8, 1925. Serial No. 1,219.

In endeavors to employ more than one grain drill, the drills have been disposed one behind the other and connected in any suitable manner, one operator manipulating both drills. The objection to this method of operating more than one drill at one time is that difficulty arises in not being able to observe whether or not the rear drill is seeding properly or as to whether there is any trash, such as straw or weeds, entangled with the rear drill. If there is any trash, this method of working two drills makes it difficult and very inconvenient to dismount the forward drill and run back and kick out the trash and while the operator is dismounted to observe whether or not the rear drill is seeding properly.

With these objections and difficulties in mind, the present invention has for its purpose to provide an improved coupling between two drills or drill sections, whereby the drills are in alignment side by side, so as to overcome the objections above pointed out.

In carrying out this scheme, the invention further aims to employ at least two sixteen-hoe grain drills in alignment side by side, their adjacent ends being spaced seven inches apart. While employing two grain drills including sixteen hoes each with a coupling connecting them, it is apparent that the coupling may be used with any construction of grain drill wherein is employed a solid axle extending from one end to the other of the drill for the reason that when the two grain drills are connected or coupled, the driving axle of each receives power from the outside wheel.

Still another purpose is to provide a coupling consisting of a depending auxiliary frame carried by the frame of one of the drills and braced relatively thereto.

The invention comprises further features and combinations of parts to be hereinafter set forth, shown in the drawings and claimed.

In the drawings:

Figure 1 is a rear view showing two grain drills coupled, portions of the central parts of both drills being cut away so that the drills may be illustrated on an enlarged scale in order to bring out the scheme of the invention.

Figure 2 is a plan view of the adjacent coupled ends of the two grain drills. 55

Figure 3 is an enlarged detail perspective view of the two frames of the grain drills with the depending frame and the supporting wheel shown.

Figure 4 is a vertical sectional view on line 4—4 of Figure 3.

Referring to the drawings, 1 and 2 designate the main frames of the two grain drills, and 3 denotes the depending frame which is secured by suitable bolts or the like 4 to the frame 2 of the right hand grain drill. The depending frame consists of the main section 5, which is approximately U-form in side view, and the auxiliary section 6. The latter section conforms to the contour of the main section 5 of the depending frame and has lateral angular ends 7 which are bolted at 8 to the main section. 70

Suitable braces 9 are secured at 10 to the auxiliary section of the depending frame 75 and are bent or suitably formed to accommodate themselves for connection to the frame of the grain drill at the right. The braces 9 are secured at 11 to the grain drill frame by suitable bolts or the like 12. Additional braces 13 and 14, angularly disposed, connect the main section of the depending frame and the front and rear bars of the frame of the grain drill to the right, suitable bolts or the like 15 being used to 85 secure the braces 13 and 14 in position.

The bolts or other fastenings which secure the depending frame to the frame of the grain drill to the right and the bolts which secure the braces 13 to the grain drill frame also act to secure hinge members 16 to the grain drill frame. By means of suitable bolts 17, additional hinge members 18 are secured to the frame of the grain drill to the left. A suitable pivot rod 19 passes 90 through the adjacent overlying ends of the hinge members and has nuts or the like for holding the rod in place, thereby connecting the hinge members and hence coupling the two grain drills relative to each other. A supporting wheel 20 carries the weight of the mechanism below the hinge members. 95

This manner of coupling the two drills enables the drills to operate in alignment, 105 avoids the operator dismounting and run-

ning to the rear to determine whether or not the drills are seeding properly and also obviates the collection of trash which usually results in an endeavor to operate one drill in the rear of another.

The invention having been set forth, what is claimed is:

The combination of a duality of axially aligned grain drills with the adjacent ends 10 of their frames pivotally connected, supporting wheels at the remote ends of the frames of said grain drills, a depending frame consisting of a U-shaped main section secured to the frame of one of the grain

drills, an auxiliary section spaced from the 15 main section but having angular ends bolted to the same, and braces secured respectively to the grain drill frame and said auxiliary section, and a supporting wheel disposed between the main and auxiliary sections of 20 the depending frame and rotatably mounted in the latter, said supporting wheel being disposed directly below the pivotal connection between the grain drill frame.

In testimony whereof he affixes his signature.

JOSEPH L. SCHRAG.
